UNITED STATES PATENT OFFICE.

THOMAS DANQUARD, OF NEW YORK, N. Y., ASSIGNOR TO THE AUTOPIANO COMPANY, A CORPORATION OF NEW YORK.

DIVIDED ACTION FOR PIANOS.

No. 887,773.

Specification of Letters Patent.

Patented May 19, 1908.

Application filed November 29, 1905. Serial No. 283,573.

To all whom it may concern:

Be it known that I, THOMAS DANQUARD, a citizen of the United States, residing at New York, in the county of New York and State of New York, have invented a new and useful Divided Action for Pianos, of which the following is a specification.

In pianos especially of that class which are provided with mechanical or pneumatic playing attachments, it is desirable to have some means by which the upper notes can be played louder than the lower notes or vice versa, so that the air or theme can be brought out and the accompaniment softened.

The object of this invention is to provide a simple mechanism directly controlling the piano action for this purpose and this controlling mechanism is also arranged so that the same is adjustable whereby the difference in action between the various sections of the piano can be adjusted, permitting very fine shading and expression. This controlling mechanism is obtained by providing means controlled by the player or operator for collectively adjusting the operative effect of the connections to a section of actions and preferably by adjusting the operative leverage in the connections.

The invention further consists of important combinations to effect these desirable purposes, as hereinafter more particularly pointed out in the specification and referred to in the claims.

Referring to the accompanying two sheets of drawings forming part of this application for patent, Figure 1 is a sectional elevation of a piano action constructed according to my invention. Fig. 2 is a partial view similar to Fig. 1 illustrating the parts in a different position, and Fig. 3 is a diagrammatic perspective view illustrating a simple form of lever action that may be used to control the adjusting mechanism.

Referring to the drawings and in detail, a single piano action of standard type is shown, the operation of which it is not necessary to describe as the same is well understood.

In this piano action, A designates the wippen or operating part which is fulcrumed or pivoted at a and B the abstract, which latter may be operated from a piano key C in the ordinary way so that the piano may be played manually as well as mechanically.

D designates motor means which may be an operating pneumatic for each key, which

pneumatics are used when the piano is to be played mechanically.

The operating rod 10 of each pneumatic engages the short end of an L-shaped bar 11. This bar has a pin 12 at its upper end which fits in a bearing piece 13 connected to the abstract B.

The bar 11 is pivoted at its lower end to a link 14 which link is pivoted on a bracket 15 secured to a cross-bar in the piano.

The abstract B is slotted so that the link 14 can pass through the same without engagement therewith.

16 designates a pushing lever which is set in position to bear on the under side of the wippen A, the wippen being cut or formed on a curve, as shown for this purpose.

The link passes through a slot 17 cut in the pushing lever 16 and is pivoted thereto by a pin 18.

The slot 17 is cut on an incline as shown more particularly in Fig. 3, and a small piece of felt 19 is arranged at the sharp end thereof so that an inclined wire spring 20 attached to the link 14 can bear thereon.

When the key C is depressed, the abstract B will raise the wippen A to operate the action and it will be noted that the mechanism before detailed will not interfere with this action.

When the note is struck mechanically through the pneumatic or other means, the operating rod 10 will lift the bar 11 which will raise the link 14 and will impart the motion through the pushing rod 16 to the wippen A. It will be noted that as this action takes place, the abstract B will merely be raised or lifted away from the key C and will not form a part of the mechanism for striking the note.

It will be noted that as the power or blow is imparted to the wippen A through the pushing bar 16, if the pushing bar is adjusted toward or away from the fulcrum a of the wippen, that the blow or impulse imparted to the striking mechanism can be varied. It also will be noted that the pushing bar 16 can be rocked on its pin or pivot 18 for this purpose. Therefore, by using this mechanism and providing suitable controlling means, the desirable effects above noted can be obtained; that is to say, the piano action can be divided into a plurality of sections and the actions of these sections relatively to the others can be adjusted when the piano is played mechanically or pneumatically by ad-

justing the pushing bars 16 of each section to get the desired result. It also will be noted that each pushing bar 16 can be adjusted within its limits of movement so that this relative ratio can be adjusted.

To operate or control the position of the pushing rods 16, the following mechanism is provided. A spring 21 is secured to the lower end of each pushing rod 16. A rod 22 has its ends turned around at 23, as shown in Fig. 3, so that the same can be pivoted in the cross-bar of the piano and so that the same can turn around the said bent ends as a center. The rod 22 is preferably provided with small pieces of felt glued thereto in proper position to coöperate with the springs 21. The rod 22 can be turned on its ends 23 by any suitable means or mechanism. A convenient form of mechanism that may be employed for this purpose is illustrated in Fig. 3. The same consists of a hook 25 which engages the rod 22, which hook is secured on shaft 26 which has a bent end 27 which is connected by link 28 to a pivoted bell-crank lever 29, which latter is connected by a link 30 to an operating finger-piece arranged at a convenient point in the reach of the operator.

The rod 22 is arranged to control a selected section of the actions. That is to say, the piano action as a whole is divided into a plurality of sections. One of these sections can alone be operated and controlled or two or more sections can be operated and controlled as indicated in Fig. 3.

When the finger-piece 31 is operated or moved, the rod 22 will be swung up as indicated in Fig. 2, thereby adjusting the action of the notes making up the particular section controlled by the rod 22. Therefore, by manipulating the finger-piece, the results above noted can be obtained.

An important point in the operation of this device results from the use of the springs 20 and 21. The spring 20 is arranged so that it will tend normally to throw the upper end of the pushing bar 16 to the right as shown in Fig. 1. The spring 21 is made more powerful than the spring 20 so that it will overbalance the spring 20, when its full strength is brought into action by swinging the rod 22.

As the rod 22 is usually operated or adjusted while the instrument is playing, the adjustment may and often will take place when one or more abstracts of the particular section is raised and one or more pushing bars 16 under tension. This would make it hard to adjust the pushing bar 16 but when the adjustment is made, the spring 21 of any particular pushing bar which happens to be raised or under pressure, will be put under tension so that so soon as the note is released, the spring 21 will bring the pushing bar to its adjusted position. Substantially

the same action will take place if the tension of the spring 21 is released when the pushing bar is under pressure so that when the pressure is released, the spring 20 will bring the pushing bar to the position which it is to assume by the adjustment of the rod 22. Thus the light and heavy springs will cause the pushing bars to assume their adjusted positions only when the particular actions are not under pressure or in operation.

It will be noted that the movable pushing bar when in normal position or forward, as shown in Fig. 1, will transmit the full power of the striking pneumatic to the hammer and that when it is moved backward or toward the fulcrum of the wippen, the leverage on the wippen is shortened and more power is required to strike the same note or the same power consequently strikes a lighter blow. Therefore, the blows on the particular section of notes of a piano can be graduated at the will of the player. Therefore, as above described, by dividing the piano action into a plurality of sections, the sections can be played differently and all the advantages of a graduated divided action obtained. Thus, by the mechanism described, a simple and effective apparatus is provided which greatly adds to the artistic effects which can be obtained in mechanically operated pianos. It will also be noted that the key action is the same no matter where the adjusting rod is left.

The operating means of course, can be of any kind; that is, the piano may be played by hand by power or by electricity as well as by pneumatics, it being understood that the impulses from the mechanism are imparted to the operating rods 10.

The details herein shown and described may be greatly modified by a skilled mechanic without departing from the scope of my invention as expressed in the claims.

Having thus fully described my invention, what I claim and desire to secure by Letters-Patent is—

1. In a musical instrument, the combination of actions, wippens therefor, abstracts pivotally connected with the wippens, additional connections for operating the actions comprising pushing bars pivoted below and engaging the wippens of the actions, and means for collectively adjusting the ends of the pushing bars which engage the wippens.

2. In a piano, the combination with the actions, of means for operating the actions comprising pivoted links, pushing bars pivotally connected with the links, springs normally tending to keep the pushing bars in one position, an adjusting rod, and springs between the pushing bars and adjusting rod.

3. In a piano, the combination with the actions, of means for operating the actions comprising pushing bars, springs normally

tending to throw the pushing bars in one direction, and springs tending to throw the pushing bars in the other direction.

4. In a piano, the combination with the actions, of means for operating the actions, comprising pushing bars, springs normally tending to throw the pushing bars in one direction, and springs tending to throw the pushing bars in the other direction when put under tension, the last named springs being of a strength sufficient to overcome the action of the first named springs.

5. In a piano, the combination of a section of actions, means for operating the actions comprising pushing bars, springs normally tending to throw the pushing bars in one direction, a rod for controlling the action of the pushing bars, and springs between the pushing bars and rod tending to throw the pushing bars in the other direction.

6. In a piano, the combination of a section of actions, means for operating the actions comprising pushing bars, springs normally tending to throw the pushing bars in one direction, a rod for controlling the action of the pushing bars, and springs between the pushing bars and rod tending to throw the pushing bars in the other direction, the springs between the pushing bars and rod being heavier or overbalancing the first named springs.

7. In a piano, the combination of a section of actions, means for operating the actions comprising pivoted links, pushing bars pivoted thereto, and connections to the pivoted links, springs normally tending to keep the pushing bars in one position, an adjusting rod, and springs between the pushing bars and adjusting rod.

40 8. In a piano, the combination of a section of actions, abstracts therefor, means for operating the actions comprising pivoted links, pushing bars pivoted to the links, and

an adjusting rod for determining the position of the pushing bars.

9. In a musical instrument, the combination with the actions, means for operating the actions comprising pivoted links, slotted pushing bars pivotally connected with the links, springs engaging the slots in the pushing bars, springs connected with the pushing bars, and an adjusting rod bearing on the last named springs.

10. In a piano, the combination of a section of actions, means for operating the actions comprising pivoted links and slotted pushing bars pivoted to said links, springs engaging the tops of said slots, springs on the end of the pushing bars, and an adjusting rod bearing on the last named springs.

11. In a piano, the combination with the actions and the abstracts therefor, said actions being divided into sections, of means for operating said sections of actions comprising pivoted links, pushing bars pivoted to the links, and a plurality of adjusting rods, one for each section of actions for determining the positions of said pushing bars.

12. In a musical instrument, the combination of the actions divided into series, wippens therefor, abstracts pivotally connected with the wippens, pivotal connections for operating the actions comprising pushing bars pivoted below and engaging the wippens of the actions, and a plurality of means, one for each section of actions for collectively adjusting the ends of the pushing bars which engage the wippens of said sections of actions.

In testimony whereof I have hereunto set my hand, in the presence of two subscribing witnesses.
